(57) **CLAIM**

The ornamental design for a battery, as shown and described.

DESCRIPTION

FIG. 1 is a top perspective view of a first embodiment of a battery showing my new design;

FIG. 2 is a bottom perspective view thereof;

FIG. 3 is a bottom elevational view thereof;

FIG. 4 is a top elevational view thereof;

FIG. 5 is a left side view thereof;

FIG. 6 is a right side view thereof;

FIG. 7 is a top plan view thereof; and

FIG. 8 is a bottom plan view thereof;

FIG. 9 is a top perspective view of a second embodiment of a battery showing my new design;

FIG. 10 is a bottom perspective view thereof;

FIG. 11 is a bottom elevational view thereof;

FIG. 12 is a top elevational view thereof;

FIG. 13 is a left side view thereof;

FIG. 14 is a right side view thereof;

FIG. 15 is a top plan view thereof; and,

FIG. 16 is a bottom plan view thereof.

The broken lines depict a portion of the battery that forms no part of the claimed design.

1 Claim, 16 Drawing Sheets
